CONTAINER FOR BOOKLETS OR THE LIKE

John E. Lawlor, Tappan, N.Y., and John E. Sgombick, Ramsey, N.J., assignors to Xerox Corporation, Stamford, Conn.

Filed Feb. 5, 1973, Ser. No. 329,799

Term of patent 14 years

Int. Cl. D9—03

U.S. Cl. D9—202

FIG. 1 is a perspective view of a container for booklets or the like in an opened condition, showing our new design;

FIG. 2 is a perspective view thereof in a closed condition;

FIG. 3 is a left side elevational view thereof; and

FIG. 4 is a right side elevational view.

We claim:

The ornamental design of a container for booklets or the like, substantially as shown and described.
